TOY AIRPLANE

Lyne T. Shackelford, Mobile, Ala.

Application July 10, 1936, Serial No. 89,912

1 Claim. (Cl. 46—79)

This invention relates to toy airplane constructions.

More particularly the invention relates to a toy airplane which may be manufactured at an exceedingly small cost while still providing a construction of unusual stability in flight and exceptionally realistic in appearance.

Toy airplanes of the class to which this invention is directed, are usually sold as novelties to children at a price of one cent or thereabouts, with the consequence that the materials used in the manufacture and assembly of the parts must be very inexpensive while at the same time to be acceptable to this trade, the article must be of a decorative and realistic appearance and capable of sustained soaring and repeated flights without damage to its construction, in the hands of inexperienced children.

The construction embodying the present invention fulfills these requirements and involves substantially a minimum number of parts, each of extreme simplicity, and of light weight, yet yieldable and not fragile.

Various further and more specific objects, features and advantages will clearly appear from the detailed description given below taken in connection with the accompanying drawing which forms a part of this specification and illustrates merely by way of example preferred forms of the invention.

The invention consists in such novel features, arrangements and combinations of parts as may be shown and described in connection with the constructions herein disclosed.

In the drawing, Fig. 1 is a perspective view of an assembled toy airplane embodying my invention in one of its forms.

Fig. 2 illustrates one of the members of the construction of Fig. 1, designed to simulate landing gear;

Figs. 3 and 4 illustrate alternative embodiments of one of the members of Fig. 1; and

Fig. 5 is a perspective view of a further alternative embodiment of the simulated landing gear construction and means for securing the same to the body or fuselage of the airplane.

As shown in Fig. 1, the construction may comprise a body or fuselage portion 10 preferably comprising a rod of balsa wood or other light weight material shaped in general conformity to the outlines of a conventional airplane fuselage. A wing member 11 may be removably secured to the fuselage member as by a rubber band or cord, as illustrated in Fig. 1. Tail pieces or rudders 55 as at 12 and 13 may be removably secured to the

rear end of the fuselage member. These members may be secured, for example, by inserting the same within longitudinally extending saw cuts, formed as illustrated, in the end of the member 10. To enhance the attractiveness of the device, the members 10 to 13 inclusive, prior to assembly, may be each distinctively colored as by inserting the members individually in baths of dye or other coloring material. All of these members are preferably formed of balsa wood or other light weight strong wood, or other substance, cut into strips as thin as possible and shaped substantially as shown.

With inexpensive constructions of this class as heretofore marketed, the forward end of the device has a tendency to rise too high for sustained flight by reason of lack of weight in the forward portions. Attempts have been made to remedy this action by inserting a tack or other small weight in the forward end of the fuselage member at the position shown in Fig. 1 to give added weight at this point, but this expedient alone, has not been entirely satisfactory. In the construction shown, I have provided in addition, at 15 an additional member of very inexpensive form to simulate landing gear, and at the same time providing a slight additional weight at the forward end of the plane and a slight added air resistance to flight at a point beneath the forward end of the fuselage. Such added resistance at this point aids in achieving greater stability of the device in flight.

The member 15 as shown in Fig. 2, may be formed of light weight sheet material such as thin cardboard or pasteboard and readily stamped with an outline, such as when the device is assembled, this member will give the appearance of streamlined wheels or other landing gear. The member 15 may include a middle or body portion 17, adapted to extend in a generally horizontal plane and to be received and removably embraced within a saw cut slot 16 extending transversely through the forward end of the fuselage member, as shown in Fig. 1, or alternatively, as shown at 16a in Fig. 3. Or if preferred, as shown in Fig. 4, a pair of saw cuts 16c may be provided as at 16b, within which the portion 17 may be removably inserted. Or the member 15 may be removably attached to the lower forward end of the fuselage member by means of a rubber band or cord similar to the attachment of member 11 by means of a rubber band or cord. The member 15 may have a pair of end portions as at 18 and 19, each having the outline of the conventional form of landing gear 55

desired to be represented, as indicated for example at 20. These end portions may be bent downwardly so as to extend in generally vertical planes substantially parallel to the direction of flight. To facilitate this bending down of the ends 18 and 19 by the customer, the member 15 may be creased as at 18a by the manufacturer. In case the bent-down ends 18 and 19 have a tendency to spread apart slightly, i. e. to positions 10 at a slight angle to the vertical, this will not detract from the realistic appearance, but rather will tend to give the landing gear a braced appearance.

In Fig. 5 I have illustrated a modified form of construction in which a member 21 of thin light weight sheet metal may be provided to give a representation of landing gear. This member may comprise a substantially horizontally extending middle portion 22 formed with a plurality of struck-up projections as at 23 having their upper ends pointed and turned inwardly as shown, for gripping the fuselage member 10. The outer ends of the member 21 may be bent downwardly as at 24, the ends being cut with an outward line as at 25 representative of wheels or other landing gear as desired.

With all of the above described embodiments of the invention, the member representing the landing gear is of such construction and is so secured to the fuselage member that the device will not be damaged even by repeated and long use in inexperienced hands. That is, the landing gear member will yield or its connection to the fuselage member will readily yield when the device falls to the earth, so that none of the parts may be easily broken with normal use of the de-

vice. Thus it will be noted that I have provided a simple means for giving the slight additional weight to the forward end of the fuselage and added resistance at a point beneath the forward end for increasing the stability of flight, but at the same time increasing the realistic appearance at an almost negligible cost. 5

While the invention has been described in detail with respect to particular preferred examples, it will be understood by those skilled in the art 10 after understanding the invention, that various changes and further modifications may be made without departing from the spirit and scope of the invention, and it is intended therefore in the appended claim to cover all such changes and 15 modifications.

What is claimed as new and desired to be secured by Letters Patent is:

A toy airplane construction comprising a rod of light weight wood shaped to represent a fuselage, 20 wing and tail pieces secured thereto, and means representative of landing gear comprising an integral piece of pliable sheet material comprising cardboard or the like, and having its midportion normally in substantially a horizontal plane, an 25 open ended saw cut extending transversely through said rod adjacent the forward end thereof, forming a slot for removably receiving and yieldably clamping said portion to said rod, the two ends of said piece of sheet material being bent 30 downwardly for extending in generally vertical planes substantially parallel to the direction of flight, the outline of said ends simulating the outline of landing gear as viewed in a direction at right angles to the direction of flight. 35
